COKE OVEN

Friedrich Totzek, Essen-Stoppenberg, Germany,
assignor, by mesne assignments, to Koppers
Company, a corporation of Delaware

Application March 30, 1931, Serial No. 526,222
In Germany March 31, 1930

10 Claims. (Cl. 202—144)

This invention consists in improvements in or relating to coke ovens of the type comprising heating walls having pairs of vertical heating flues which communicate with each other near the top and bottom and of which at any moment one contains ascending and the other descending gases. A coke oven having a heating wall of this construction will be referred to hereinafter as a coke oven of the type specified.

10 Gas and air are supplied for a time to the bottom of that heating flue (of a pair) in which burning takes place, while the products of combustion are removed from the bottom of the other heating flue of the same pair. After a time the process is reversed and the gases flow in opposite directions.

20 The object of the communicating passage between the two flues at their lower ends is to enable burnt gases to pass from the down-flow flue into the up-flow flue. Such an addition of burnt gases dilutes the mixture of gas and air and results in retardation of combustion and in the formation of a longer flame extending up the up-flow flue. This is of particular importance when the heating of the oven is effected with rich gas which would otherwise tend to form a very short flame.

25 It has now been found that this advantageous effect is obtained in a particularly high degree by 30 the present invention according to which the admission passages for air and gas are so situated in relation to the lower opening between pairs of flues that waste gases from the down-flow flue enter the up-flow flue between the currents of rich gas and of air for combustion as they enter the up-flow flue.

35 Thus, in one construction according to the invention an admission passage for rich gas and an admission passage for air open into a heating flue at positions spaced apart in a horizontal direction parallel with the width of the separating wall sufficiently and widely apart that the lower communication opening is so situated in relation to them as to direct at least a portion of the circulating gas between the streams of rich gas and air issuing from their respective admission passages.

40 Preferably, a weak gas (lean fuel-gas) admission passage and an air admission passage are situated close to one another and/or level with one another in a horizontal direction parallel to the side of the heating wall, that is to say, in a direction at right angles to the general plane of the division wall between the pairs of flues. The 45 passages for the admission of weak gas (lean

fuel-gas) and air conveniently join before opening into the heating flue so as to form a mixing nozzle.

5 In order that the invention may be more readily understood a specific example thereof will now be described with reference to the accompanying drawing, in which—

Figure 1 is a longitudinal vertical section (on the line 1—1 of Figure 2) through a part of the heating wall of a coke oven embodying the invention; 10

Figure 2 is a sectional plan on the line 2—2 of Figure 1, and

Figure 3 is a section on the line 3—3 of Figure 2. 15

Like reference numerals indicate like parts in all the figures of the drawing.

The heating flues are shown as arranged in pairs, each pair comprising a flue 11 and a flue 12. These flues are separated by a wall 14 having 20 in it an opening 13 at its upper end and an opening 18 at its lower end. At the bottom of each flue are three admission passages, a passage 15 for air, a passage 16 for air or weak gas and a passage 17 for rich gas. The passages 15 and 16 are adapted on reversal of the regenerators to serve also as exhaust passages for waste gas while the passages 17 remain idle. The passages 15, 16 and 17 are therefore constituted of passages PA adapted during one regenerator period 30 for inflow of air, PAWG adapted for inflow of air or weak gas, and PG adapted for inflow of rich gas, and passages PW for exhaust of waste gas and PI for passages that are idle. On reversal said passages are adapted for operation as passages constituted as indicated by the legends in dotted lines. 35

As illustrated, the oven comprises oven-chambers such as 20 divided from one another by heating walls each containing flues such as 11 and 12 40 above referred to, and regenerators situated below the oven-chambers each divided into halves 21 and 22 by a central partition wall 23 running the whole length of the oven battery transverse to the lengths of the respective oven-chambers. 45

At any moment all the regenerators on one side of this wall 23 are serving to preheat air or weak gas while all those on the other side are being heated by exhaust gases. When heating with preheated weak gas the latter is supplied to alternate regenerators on one side of the wall 23 50 while air is supplied to the remaining regenerators on the same side of this wall. Thus, each heating flue is connected so as to be supplied from or to exhaust into two adjacent regener- 55

ators. As shown clearly in the drawing, the flues 12 are each supplied directly from two adjacent regenerators 21 through the passages 15 and 16. The flues 12 in the right half of the heating wall are supplied from the same pair of regenerators 21 by means of extension passageways 24 communicating with their respective regenerators 21 and lying above the companion regenerators 22. Similarly, the flues 11 communicate, through passages 15, 16 with adjacent regenerators 22, those on the right half of the heating wall communicating directly with the regenerator-chambers, while those on the left communicate with the same regenerators 22 by means of branch passages 25 leading from the regenerators 22 and lying above the companion regenerators 21.

The rich gas is supplied by means of conduits 26 with which the passages 17 are in communication. Each conduit 26 is of course connected to a rich gas main, diagrammatically indicated at 26' in Fig. 2.

In operation, gas and air are admitted through the passages at the bottom of one set of flues, say 11, for a time. As they ascend in these flues they burn and the products of combustion pass over into the other companion flues 12 through the upper openings 13. The gases travel down through the flues 12 and out through passages 15 and 16 at the bottoms of those flues. After a time the gas currents are reversed and gases for combustion are supplied to and rise in the flues 12 while products of combustion descend the flues 11.

The fact that burning gases, in what is for the time being the up-flow flues—say 11—are hotter and, therefore, lighter, than the products of combustion in the down-flow flues 12 causes a circulation of waste gases to take place from the bottoms of the down-flow flues through the lower communication openings 18 in the bottoms of the up-flow flues.

As shown most clearly in Figure 2, the admission passages 15 and 16 are situated close together and level with one another in a horizontal direction parallel to the length of a heating wall. Moreover, as shown in Figure 1, these two passages join one another in pairs before opening into the soles of the heating flues and thus constitute mixing nozzles in which, when the flues are to be heated by means of weak gas, weak gas preheated in alternate regenerator chambers, and air preheated in the intermediate regenerator-chambers on one side of the partition wall 23, may meet and commence to burn (in up-flow flues) before mixing with waste gases (from adjacent down-flow flues) entering through lower openings 18. Thus, the latter gases do not substantially retard the combustion of the weak or lean gas which in any case burns with a relatively long flame and results in more or less uniform heating of the flues.

When employing rich gas to heat the oven, the gas is introduced through passages 17 while air preheated now in all the regenerator-chambers on one side of the wall 23 will enter through both openings 15 and 16 of each pair.

As can be seen clearly from Figure 2, the passages 17 are separated apart widely from the passages 15 and 16 in a horizontal direction parallel to the width of the separating wall 14. Thus, the waste gas circulating through each of the lower communication openings 18 flows between the streams of rich gas and air and retards their intermixing and hence their burning thereby

greatly lengthening what otherwise would be a short hot flame.

It will be appreciated that the details of construction may be modified in many ways. For example, the admission passages need not necessarily open into the bottom of the heating flue but might be arranged in some other part of the heating flue walls of which the sole is to be taken as one example.

I claim:

1. A coke oven having combustion flues with circulating gas passages communicating with the flues through inlet and outlet openings therefor for circulation of gases through the respective flues, each flue having two inlet ports for admission of air and rich gas to the flues so situated in relation to the inlet openings for the flues that circulating gas passing through the inlet opening of a flue may be directed into the latter between the currents that may issue from the respective inlet ports into the flue for inflow of rich gas and air, the rich gas main communicating with its rich gas port and having no other communication with the stack or oven.

2. A coke oven having combustion flues with circulating gas passages communicating with the flues through inlet and outlet openings therefor for circulation of gases through the respective flues, each flue having three inlet ports for admission of air and rich gas or air and weak gas to the flues, the air and rich gas ports being so situated in relation to the inlet openings for the flues and to each other that circulating gas passing through the inlet opening of a flue may be directed into the latter between currents that may issue from the respective inlet ports into the flue for inflow of rich gas and air, and the weak gas and air inlet ports for each of the flues being situated relative to the inlet opening of the flue and joining one another before opening into the flue to form a mixing nozzle whereby currents that may issue separately and simultaneously through the inlet ports for weak gas and air meet in the nozzles before meeting gas issuing into the flue from the inlet opening.

3. A coke oven having combustion flues operatively disposed in two sets operable for simultaneous inflow combustion and outflow of combustion products in alternation with each other and with inlet and outlet openings communicating the flues of said two sets for circulation of combustion products through the respective flues, each flue having at least two inlet ports for separate and simultaneous admission of air and rich gas to the flues so situated in relation to the inlet openings for the flues that circulating gas passing through the inlet opening of a flue may be directed into the latter between the inlet ports for admission of air and rich gas, the rich gas main communicating with its rich gas port and having no other communication with the stack or oven.

4. A coke oven having combustion flues operatively disposed in two sets operable for simultaneous inflow combustion and outflow of combustion products in alternation with each other and with inlet and outlet openings communicating the flues of said two sets for circulation of combustion products through the respective flues, each flue having three inlet ports for optional separate and simultaneous admission of air and rich gas or separate and simultaneous feeding of air and weak gas to the flues, the air and rich gas ports being so situated in relation to the inlet openings for the flues and to each other that

circulating gas passing from a flue of one of the sets through the inlet opening of a flue of the other set may be directed into the latter between the inlet ports for admission of rich gas and air into the flue, and the weak gas and air inlet ports for each of the flues being situated relative to the inlet opening of the flue and joining one another before opening into the flue to form a mixing nozzle whereby weak gas and air from the inlet ports therefor will meet in the nozzle before meeting gas issuing into the flue from the inlet opening.

5. A coke oven of the type specified having vertical heating flues therefor operatively disposed 15 in pairs operable concurrently for upflow combustion and downflow of combustion products in alternation with each other, with upper and lower openings in a wall separating the flues of a pair at the upper and lower parts of the paired 20 flues for communicably connecting the flues of a pair with each other for circulating gaseous combustion products from the upper part of each flue of a pair when operated for upflow to the upper part of the other flue of the pair and 25 thence from the lower part of said other flue into the lower part of the flue of the pair operated for concurrent upflow, and having rich fuel gas and air inlet ports for inflow of air and of unpre- 30 heated rich fuel gas to each flue of each pair, 35 the air and rich fuel gas ports for each flue of a pair being so situated in relation to each other and to the lower opening between the pair of flues that the circulating gaseous combustion products when passing from each flue of a pair 40 when operated for downflow into the other flue of the pair will be directed into the flue, operated for concurrent upflow, between the currents that may issue simultaneously from the rich fuel gas and air inlet ports, the rich gas main communicating with its rich gas port and having no other communication with the stack or oven.

6. A coke oven of the type specified having vertical heating flues therefor operatively disposed 45 in pairs operable concurrently for upflow combustion and downflow of combustion products in alternation with each other, with upper and lower openings in a wall separating the flues of a pair at the upper and lower parts of the paired flues for communicably connecting the 50 flues of a pair with each other for circulating gaseous combustion products from the upper part of each flue of a pair when operated for upflow to the upper part of the other flue of the pair and thence from the lower part of said other flue into the lower part of the flue of the pair 55 operated for concurrent upflow, and having rich fuel gas and air inlet ports for inflow of air and of unpreheated rich fuel gas to each flue of each pair opening into their respective heating flues 60 at positions spaced sufficiently wide apart in a horizontal direction parallel with the width of the wall separating the flues of the pair and the air and rich fuel gas ports for each flue of a pair being so situated in relation to each other and to the 65 lower opening between the pair of flues that at least a portion of the circulating gaseous combustion products when passing from each flue of a pair when operated for downflow into the other flue of the pair will be directed into the flue, operated for concurrent upflow, between the currents that may issue simultaneously from the rich fuel gas and air inlet ports, the rich gas main 70 communicating with its rich gas port and having no other communication with the stack or oven.

7. A regenerative coke oven of the type speci-

fied having vertical heating flues therefor operatively disposed in pairs operable concurrently for upflow combustion and downflow of combustion products in alternation with each other, with upper and lower openings in a wall separating the flues of a pair at the upper and lower parts of the paired flues for communicably connecting the flues of a pair with each other for circulating gaseous combustion products from the upper part of each flue of a pair when operated for upflow to the upper part of the other flue of the pair and thence from the lower part of said other flue into the lower part of the flue of the pair operated for concurrent upflow, and having rich fuel gas, regenerator air and optionally operable regenerator fuel gas inlet ports for firing each flue of a pair optionally with unpreheated fuel gas or regeneratively preheated fuel gas, the regenerator air and rich fuel gas inlet ports for each flue of a pair being so situated in relation to each other and to the lower opening between the pair of flues that the circulating gaseous combustion products when passing from each flue of a pair when operated for downflow into the other flue of the pair will be directed into the flue, operated for concurrent upflow, between the currents that may issue concurrently from the rich fuel gas and regenerator air inlet ports, and the regenerator fuel gas and regenerator air inlet ports for each flue of a pair being so situated close to one another and in relation to the lower opening that circulatory gas from the flues when operated for downflow will not enter the flue, operated concurrently for upflow, between currents that may issue simultaneously from the regenerator air and regenerator fuel gas inlet ports.

8. A regenerative coke oven of the type specified having vertical heating flues therefor operatively disposed in pairs operable concurrently for upflow combustion and downflow of combustion products in alternation with each other, with upper and lower openings in a wall separating the flues of a pair at the upper and lower parts of the paired flues for communicably connecting the flues of a pair with each other for circulating gaseous combustion products from the upper part of each flue of a pair when operated for upflow to the upper part of the other flue of the pair and thence from the lower part of said other flue into the lower part of the flue of the pair operated for concurrent upflow, and having rich fuel gas, regenerator air and optionally operable regenerator fuel gas inlet ports for firing each flue of each pair optionally with unpreheated fuel gas or regeneratively preheated fuel gas, the regenerator air and rich fuel gas inlet ports for each flue of a pair being so situated in relation to each other and to the lower opening between the pair of flues that the circulating gaseous combustion products when passing from each flue of a pair when operated for downflow into the other flue of the pair will be directed into the flue, operated for concurrent upflow, between the currents that may issue concurrently from the rich fuel gas and regenerator air inlet ports, and the regenerator fuel gas and regenerator air inlet ports for each flue of a pair being situated relative to the lower opening and joining one another to form a mixing nozzle so as to mix fuel gas and air before discharge into that portion of the flue where the lower opening discharges.

9. A regenerative coke oven of the type specified having vertical heating flues therefor oper-

atively disposed in pairs operable concurrently for upflow combustion and downflow of combustion products in alternation with each other, with upper and lower openings in a wall separating the flues of a pair at the upper and lower parts of the paired flues for communicably connecting the flues of a pair with each other for circulating gaseous combustion products from the upper part of each flue of a pair when operated for upflow to the upper part of the other flue of the pair and thence from the lower part of said other flue into the lower part of the flue of the pair operated for concurrent upflow, each flue having rich fuel gas, regenerator air and optionally operable regenerator air and fuel gas passage with inlet ports for firing each flue of each pair optionally with unpreheated fuel gas or regeneratively preheated fuel gas, the regenerator air and rich fuel gas inlet ports for each flue of a pair being so situated in relation to each other and to the lower opening between the pair of flues that the circulating gaseous combustion products when passing from each flue of a pair when operated for downflow into the other flue of the pair will be directed into the flue, operated for concurrent upflow, between the currents that may issue concurrently from the rich fuel gas and regenerator air inlet ports, and the regenerator fuel gas and regenerator air inlet ports for each flue of a pair being so situated in relation to one another and to the lower opening that circulating gas passing through the lower opening from each flue of a pair when operated for downflow will not be directed into the other flue of the pair between the currents that may issue simultaneously from the regenerator fuel gas and regenerator air inlet ports for the flue, operated for upflow, and the regenerator fuel gas and regenerator air inlet ports for each flue of each pair being arranged in relation to the lower openings of the flues of each pair so that the regenerator fuel gas inlet port for each flue is situated

between the regenerator air inlet port thereto and the lower opening.

10. A coke oven battery comprising, in combination: a series of alternate coking chambers and heating walls therefor arranged side-by-side in a row; two series of regenerators situated below the oven separated by a wall longitudinally of the battery and operable for concurrent inflow preheating and outflow of waste gas in alternation with each other; each of said heating walls comprising a row of vertical hairpin-combustion flues, the two limbs of each hairpin-flue being operable for concurrent upflow combustion and downflow of combustion products in alternation with each other, there being hairpin flues along portions of the coking chambers on opposite sides of the separating wall; extension passageway means extending from each regenerator between the upper portion of a regenerator of the other series and the levels of the bottoms of the flues in the portion of the oven above said series; one limb of each of the aforesaid hairpin flues communicating at its lower end directly with a regenerator of the series on the same side of the battery that the hairpin flue is on and the other limb of each hairpin flue communicating at its lower end through an extension passageway with a regenerator of the other series; each of said hairpin flues having upper and lower openings in their upper and lower parts for communicably connecting the two limbs of each hairpin flue with each other for flow of waste gas from each limb at its upper part, when operable for upflow combustion, to the other limb, operable concurrently for downflow of combustion products, at its upper part, and for recirculation of part of the waste gas from the lower part of the limb operable for downflow of combustion products into the lower part of the limb operable for concurrent upflow combustion.

FRIEDRICH TOTZEK.
